UNITED STATES PATENT OFFICE.

CHARLES S. LOCKE, OF JOLIET, ILLINOIS.

ANCHOR FOR CHECK-ROW WIRES.

SPECIFICATION forming part of Letters Patent No. 292,832, dated February 5, 1884.

Application filed October 20, 1883. (No model.)

To all whom it may concern:

Be it known that I, CHARLES S. LOCKE, a citizen of the United States of America, residing at Joliet, in the county of Will and State 5 of Illinois, have invented certain new and useful Improvements in Anchors for Check-Row Wires, of which the following is a specification, reference being had therein to the accompanying drawings.

10 Figure 1 is a front perspective view, and Fig. 2 a rear perspective view.

This invention relates to certain improvements in anchors for check-row wires to operate a check-row attachment for seed-planters, 15 and is of that class in which a tongue, to the upper end of which the check-row wire is attached, is pivoted to the earth at the foot and swings from one side to the other, to carry the check-row wire forward to be in line with the 20 advancing or approaching planter, the particular improvements in which I will proceed to explain.

Referring to the drawings, *a* represents the tongue pivoted at *R'* to a beam, *B*, which lies on the earth, and having a slit, *w'*, in its upper end to receive the wire *w*, and having a guy-rope, *c*, attached on its rear side near the top, and to a pin, *P'*, in the earth, to support it and counteract the strain of the check-row wire 30 *w* from the front. The beam *B* is provided with a bolt, *R*, having an eye to drive a pin through into the earth, to fasten the beam *B* firmly to the earth. The ends of the beam *B* are provided with the supports or rests *S S*, to 35 support the tongue, and hold its outer end bearing the wire *w* up off the ground, to hold the wire *w* upon a line with the approaching planter, and to render it easy for the approaching planter, by means of the wire *w*, to swing the 40 tongue *a* over onto the opposite rest. It is in these rests that my improvement principally lies, and in the bed-beam *B*, for supporting both

the tongue *a* and rests *S S* and furnishing better means for pivoting the tongue to the earth.

Fig. 2 shows but one rest, *S*, and only one- 45 half of the beam *B*. It not positively necessary to have but one rest, for the reason that the machine always leaves the tongue, while its outer end is supported on a rest. When it returns it will swing the tongue over on the 50 ground, as is shown in Fig. 2 by the dotted lines. By the tongue being upon the rest it makes it easy to swing the tongue over, because it is that much on its journey over, and it is not really necessary that the check-row 55 wire should be held up on a line with the planter as it approaches. The use of the rests is principally to hold the outer end of the tongue up a ways off the ground, so it will start to swing over more easily than it would if it lay 60 on the ground.

I am aware that cross-bars attached to the tongue have been used for this purpose, which means of support of course I do not claim; but I am not aware of the use of rests attached to 65 the bed piece or beam *B* for their support and to support the tongue ever having been used; and the advantages of this support over that named are very appreciable.

Having thus described my invention, what I 70 claim as new, and desire to secure by Letters Patent, is as follows, to wit:

In the anchor for check-row wires described, a beam, *B*, having a tongue, *a*, pivoted thereto, and a pin, *P*, for securing it in a horizontal 75 position in the earth, and provided with an upturned arm or rest, *S*, secured to its outer end or ends, forming a support for said pivoted tongue, for the purpose set forth.

CHARLES S. LOCKE.
